J. P. BESSIRE

EVERGREEN BLANKET

Filed Dec. 8, 1922

Inventor,
Jules P. Bessire,
By Joseph W. Hartman
Attorney.

UNITED STATES PATENT OFFICE.

JULES P. BESSIRE, OF INDIANAPOLIS, INDIANA.

EVERGREEN BLANKET.

Application filed December 8, 1922. Serial No. 605,738.

To all whom it may concern:

Be it known that I, JULES P. BESSIRE, a citizen of the United States, residing at Indianapolis, in the county of Marion and State of Indiana, have invented new and useful Improvements in Evergreen Blankets, of which the following is a specification.

The object of this invention is to provide a blanket for decorative purposes comprising a strong, durable body portion which is flexible and more or less elastic, to permit the finished article to be rolled for shipment and storage, and unrolled for use, and also bent to conform with the surface to be covered by it, said body material having a covering of laminiferous material such as evergreens and foliage of various trees, flowers, or the like, secured to its outer surface to present a mass of said covering material to the eye.

A further object is to provide means for stiffening and strengthening the body-material and for the secure engagement therewith of holding devices by which the blanket is pinned to the ground or other surface covered by it.

I accomplish the above, and other objects which will hereinafter appear, by the means illustrated in the accompanying drawings, in which—

Fig. 1 is a perspective view of my invention in use as a blanket for covering graves, a portion of the ground being broken away to show the holding-pin. Fig. 2 is a top plan view of my invention showing the body portion partly covered with evergreens, and Fig. 3, is an under side view of same.

Like characters of reference indicate like parts in the several views of the drawings.

The preferred material for the body or frame of my blanket is woven wire fabric 4 of open mesh similar to that commercially known as chicken wire. This may be of any desired width and length and will preferably be bound around the edges with a marginal wire or wires 5, to which the edges are secured by bending them around wires 5.

To one side of the frame or skeleton thus formed, a covering of laminiferous material 6, is fastened by sewing the stems or strongest portions thereof to the wire fabric 4. This is preferably done by a stitching of fine wire 7 which is basted back and forth

through the meshes of the wire fabric and across the stems of the foliage. In practice 55 I have found that the foliage from a species of American pine known as lycopodium, dyed a brilliant green color, makes a beautiful blanket which is durable and is practically non-inflammable. But autumn leaves 60 of any kind, holly, the usual pine and cedar evergreens, and flowers, may be used with excellent effect and with varying degrees of durability.

The blanket material thus completed may 65 be rolled up for storage and transportation, and when unrolled may be used for lining graves, for outdoor carpets covering fresh earth, and the like, for covering graves at all seasons of the year, and in innumerable 70 desirable and pleasing ways.

When it is used out of doors where it is subject to wind and other disturbances, it is preferably fastened to the ground by pins 10, here shown as having end hooks 11, 75 and cork-screw bodies as shown in Fig. 1, by which the pins are more readily inserted and more securely held; and the blanket is attached by hooking pins ends 11 around the marginal wire 5. Should there be no 80 marginal wire the hook may engage the woven body 4.

Having thus fully described my invention, the details of which are capable of variation as I have in part herein above indicated, 85 what I claim as new, is—

1. A flexible blanket conforming to the shape of a grave-mound, comprising a wire fabric body having a flexible and elastic marginal binding wire, a cover of laminiferous material sewed to the wire fabric, and pins entering the earth and removably secured to the body fabric to hold the blanket in place.

2. A flexible blanket conforming to the 95 shape of a grave-mound, comprising a wire fabric body having a flexible and elastic marginal binding wire, a covering of laminiferous material fastened to the outer side of the wire fabric, and spiral pins entering 100 the ground and having hooks engaging the marginal binding wire.

Signed at Indianapolis, Indiana, this the 5th day of December, 1922.

JULES P. BESSIRE.
